The ornamental design for an oval double ended LED light bulb, as shown and described.

DESCRIPTION

FIG. 1 is a perspective view of an oval double ended LED light bulb showing an example embodiment of the new design;

FIG. 2 is a front side elevation view of the oval double ended LED light bulb shown in FIG. 1;

FIG. 3 is a back side elevation view of the oval double ended LED light bulb shown in FIG. 1;

FIG. 4 is a left side elevation view of the oval double ended LED light bulb shown in FIG. 1;

FIG. 5 is a right side elevation view of the oval double ended LED light bulb shown in FIG. 1;

FIG. 6 is a top plan view of the oval double ended LED light bulb shown in FIG. 1;

FIG. 7 is a bottom plan view of the oval double ended LED light bulb shown in FIG. 1;

FIG. 8 is a perspective view of an oval double ended LED light bulb showing another example embodiment of the new design;

FIG. 9 is a front side elevation view of the oval double ended LED light bulb shown in FIG. 8;

FIG. 10 is a back side elevation view of the oval double ended LED light bulb shown in FIG. 8;

FIG. 11 is a left side elevation view of the oval double ended LED light bulb shown in FIG. 8;

FIG. 12 is a right side elevation view of the oval double ended LED light bulb shown in FIG. 8;

FIG. 13 is a top plan view of the oval double ended LED light bulb shown in FIG. 8;

FIG. 14 is a bottom plan view of the oval double ended LED light bulb shown in FIG. 8;

FIG. 15 is a perspective view of an oval double ended LED light bulb showing yet another example embodiment of the new design;

FIG. 16 is a front side elevation view of the oval double ended LED light bulb shown in FIG. 15;

FIG. 17 is a back side elevation view of the oval double ended LED light bulb shown in FIG. 15;

FIG. 18 is a left side elevation view of the oval double ended LED light bulb shown in FIG. 15;

FIG. 19 is a right side elevation view of the oval double ended LED light bulb shown in FIG. 15;

FIG. 20 is a top plan view of the oval double ended LED light bulb shown in FIG. 15;

FIG. 21 is a bottom plan view of the oval double ended LED light bulb shown in FIG. 15;

(Continued)

FIG. 22 is a perspective view of an oval double ended LED light bulb showing yet another example embodiment of the new design;

FIG. 23 is a front side elevation view of the oval double ended LED light bulb shown in FIG. 22;

FIG. 24 is a back side elevation view of the oval double ended LED light bulb shown in FIG. 22;

FIG. 25 is a left side elevation view of the oval double ended LED light bulb shown in FIG. 22;

FIG. 26 is a right side elevation view of the oval double ended LED light bulb shown in FIG. 22;

FIG. 27 is a top plan view of the oval double ended LED light bulb shown in FIG. 22; and,

FIG. 28 is a bottom plan view of the oval double ended LED light bulb shown in FIG. 22.
